Primary Examiner — Robert M Spear*Assistant Examiner* — Darcey E Heflin(57) CLAIM

I claim the ornamental design for the sock having camouflaged surfaces, as shown and described.

DESCRIPTION

FIG. 1 is a front view of the sock having camouflaged surfaces.

FIG. 2 is a left side view of the claimed design.

FIG. 3 is a right side view of the claimed design.

FIG. 4 is a top view of the claimed design.

FIG. 5 is a bottom view of the claimed design; and,

FIG. 6 is a perspective view of the claimed design.

The broken lines of FIG. 1 and FIG. 6 represent stitching and are a part of the claimed design.
